UNITED STATES PATENT OFFICE.

WILLIAM R. WILKES AND ALEXANDER KENNEDY, OF CLEVELAND, OHIO, ASSIGNORS
OF ONE-THIRD TO ALBERT W. McCOY, OF WILLIAMSPORT, PENNSYLVANIA.

WINDOW SASH.

Application filed June 14, 1923. Serial No. 645,424.

The present invention relates to an improvement in windows, and in general the object is to provide a window sash of simple construction adapted to permit the pane of glass within the sash to be conveniently removed and replaced. As constructed, the glass may be inserted or removed very readily either prior or subsequent to the mounting of the sash within a window frame, and the sash is especially designed to facilitate the removal of the glass when the sash is within the frame, thereby permitting the glass to be handled, washed and cleaned apart from the sash and then returned to the sash all without exposing the operator to any risk or danger by stepping out or sitting on the ledge outside of the frame. The conception further involves the making of a sash with a slotted top rail and a detachable top strip whereby a strong and rigid sash of rectangular form is obtained, and wherein the slotted top rail will guide a large sheet of glass and protect it from breaking when introducing it into or removing it from the sash, and wherein the detachable top strip will strengthen and permit the slotted rail to withstand lifting stresses, and also cover and guard the slot and top edge of the glass and hold the glass in place within the sash.

In the accompanying drawing, Fig. 1 is a reduced front view of a window frame containing a pair of sliding sashes embodying our improvement. Fig. 2 is an enlarged 35 horizontal cross section of one side rail of a sash on line 2-2 of Fig. 4. Fig. 3 is a perspective view of a portion of a sash with the glass removed and the guard strip raised apart therefrom. Fig. 4 is a vertical section 40 and perspective view of a sash with a pane of glass secured therein.

The sash comprises a horizontal grooved base strip 2, grooved upright side pieces 3-3, and a pair of spaced cross strips 4-4 uniting the upper ends of the side pieces 3-3 rigidly together and providing a narrow slot 5 vertically and longitudinally at the top of the sash which is open to the upper ends of the vertical grooves 7-7 in the side pieces 3-3. The slot and grooves in the sash are adapted to receive and hold a sheet of glass 6-6 with a snug sliding fit, and the upper edge 9 of the glass extends to and is sub-

stantially flush with the flat top surfaces 10 of the connecting strips 4 upon which a separate detachable rail or strip 11 is adapted to be seated. Rail 11 covers and closes slot 5 and is provided at its opposite ends with flat depending tongues 12 of metal, and the upper end of each side piece 3 is slotted to 55 a substantial depth opposite the vertical edge groove 7 therein to receive the tongue 12. A screw-threaded opening 14 within each tongue 12 registers or comes opposite an opening 15 in each side piece 3 to permit two 60 screws 16 to be used to fasten the guard rail 11 securely but detachably in place.

Both the upper and lower sashes A and B in a window frame C may be constructed as above described, and the advantages of 70 the improvement are as follows: In installing a window the sashes (without the glass) may be fitted and placed within the runways and connected to weights as usual. Clean sheets of glass may then be inserted 75

through slots 5, and the guard rails or strips secured in place. If sash fastening are used, these can be mounted upon the guard rails 11 in the same way as generally practiced. When the sashes are unlocked to 80 permit them to be raised or lowered it is not an unusual proceeding for the operator to grip the top cross strip in lifting the sash,

and if the sash is tight fitting or jambed the pressure on this cross strip is considerable 85 and very apt to break especially if it is subdivided to provide a vertical slot to permit the glass to be removed as in the present case. But by using a supplemental single

heavier guard rail or strip 11 the weaker 90 cross connecting pieces are re-enforced and such danger of breakage avoided. The sheet of glass may also be readily removed from the sash for cleaning after the window is installed by merely detaching the guard 95 rail, and in withdrawing the glass from the slot the double connecting strips guide and prevent a wide sheet of glass from buckling at its middle. When the glass is again inserted and the guard rail fastened in place 100 the sheet of glass is locked in place and the slot covered and protected, and inasmuch as the fastening screws are exposed only upon the inside face of the sash the glass can not be removed from the outside by thieving or 105 designing persons. As regards appearance,

the sashes although constructed differently do not differ much in appearance from the ordinary sashes in common use, the only visible difference being the line of union of the guard rail and the screws at each side. Viewed in its entirety the sash is simply constructed, may be readily substituted for the sashes commonly used, permits the glass to be removed and replaced with convenience and despatch, and no putty or other fastening means are required to secure the glass in place other than the simple and effective means herein described. When the pane of glass in a sash of this kind is broken, quick repairs and replacements can be made by anyone without tools other than a screw driver. Provision is also made to permit water to drain freely from the grooves holding the glass. That is to say, the grooves 7 in the side pieces of the sash extend through the bottom strips at 18 and prevent the water from collecting in the grooves, see Fig. 3.

What we regard as our invention or discovery and desire to claim, is:

A window sash, comprising a grooved frame having a slotted cross piece at its top, adapted to removably receive and seat a sheet of glass, the upper ends of said side pieces of said frame being slotted additionally to a greater depth, a detachable reinforcing and covering guard rail for said slotted cross piece having depending metal tongues at its opposite ends corresponding in thickness to said sheet of glass adapted to extend into the slots in the top of the side pieces of the frame and below said slotted cross piece, said metal tongues forming continuations of said side pieces when in place, and screws extending horizontally through the slotted ends of said side pieces in detachable connection with said tongues.

In testimony whereof we affix our signatures hereto.

WILLIAM R. WILKES.
ALEXANDER KENNEDY.
